BOTTLE CLOSURE

Bernard T. E. Picot, Paris, France, assignor to Christian Dior Perfumes Corp., New York, N.Y., a corporation of New York

Filed July 19, 1962, Ser. No. 70,979

Term of patent 14 years

(Cl. D58—26)

FIG. 1 is a perspective view of a bottle closure embodying my new design;

FIG. 2 is a side elevational view;

FIG. 3 is another side elevational view turned 45 degrees from the position of FIG. 2;

FIG. 4 is a top plan view; and

FIG. 5 is a bottom plan view thereof.

The broken line showing of a bottle in FIG. 1 is for illustrative purpose only.

The characteristic features of the design reside in a closure having the overall appearance of a truncated, downwardly and outwardly tapered cone having equally spaced circumferential planar facets, each facet being downwardly and outwardly inclined and extending from the top edge of the closure to a point slightly above the bottom edge thereof all as shown.

I claim:

The ornamental design for a bottle closure, as shown and described.
